Application March 31, 1948, Serial No. 18,116

7 Claims. (Cl. 98—40)

1

This invention relates to air outlet devices for controlling the delivery of air from air supply ducts into rooms or other enclosures for heating, cooling, ventilating or other purposes, and has particular reference to improvements in air outlet devices of the type comprising an outermost, open-ended member, a second member spaced from said outermost member to provide between said members an air passageway through which some or all of the air may flow, and, if desired, one or more other members spaced from said second member, and from each other, as the case may be, to provide one or more additional passageways through which part of the air may flow.

In such air outlet devices the second member may be formed or arranged relative to the outermost member so that it causes air flowing through the passageway between the same and said outermost member to be deflected laterally outward. Also, the front or outer end portion of the outermost member may be formed to intercept air flowing through the passageway between said outermost and said second members and to deflect such air forwardly from the device. Accordingly, if the second member is positioned to deflect air against the front end portion of the outermost member, the air will be caused by said front end portion to flow more or less directly forwardly from the device. If, on the other hand, the second member is positioned to deflect the air laterally outward across the front end of the outermost member, the latter will have little or no effect upon the direction of the air flow and consequently the air will flow substantially only laterally outward from the device. Intermediate positions of the second member will, of course, result in its cooperation with the front end portion of the outermost member to cause the air to be delivered in intermediate directions from the device.

In the use of a device of the type mentioned it sometimes may be desirable to have the air delivered more or less only directly forwardly from the device and, at other times, more or less only laterally outward from the device, while at other times it may be desirable to have the air delivered from the device in some intermediate direction. Accordingly, one special and important object of the present invention is to provide an air outlet device of the type mentioned embodying simple, practical means for mounting the second member for longitudinal adjustments relative to the outermost member to vary the direction of flow of air from the device, and further embodying simple, practical, readily accessible and easily oper-

2

ated means whereby such adjustments of the second member may be effected with facility.

In any instance where a device of the type mentioned comprises, in addition to a second, adjustable member, one or more other members spaced from the second member, another special and important object of the invention is to provide simple, practical means for mounting the said other member, or members, securely in desired relationship to each other and to the outermost members. Additionally in this connection, another special and important object of the invention is to provide simple, practical means whereby the second member and any additional members may be secured as a unit quickly, easily and securely to the outermost member and may equally as quickly and easily be removed as a unit from said outermost member to afford ready access to the elements of said unit and to the outermost member for cleaning, repair or other purposes as well as to facilitate installation of the device.

In some instances it may be desirable to use in association with an air outlet device of the type mentioned, a damper of any suitable type to regulate flow of air from an air supply duct to the air outlet device, and in this connection another special and important object of the invention is to so construct the air outlet device that it may serve as a positioning and guiding means for means to adjust the damper.

With the foregoing and other objects in view, which will become more fully apparent as the nature of the invention is better understood, the same consists in an air outlet device and, if desired, an associated damper, as illustrated by way of example in the accompanying drawings and embodying the novel features of construction, combination and arrangement of parts as will be hereinafter more fully described and claimed.

In the accompanying drawings, wherein like characters of reference denote corresponding parts in related views:

Fig. 1 is a central, longitudinal section through an air outlet device and an associated damper constructed in accordance with the invention.

Fig. 2 is a transverse section on the line 2—2 of Fig. 1.

Fig. 3 is a central, longitudinal section on an enlarged scale through the central portion of the air outlet device.

Fig. 4 is a detail perspective view showing the construction and arrangement of the inner end portions of the spider arms of the air outlet device.

Fig. 5 is a view similar to Fig. 3 illustrating an

alternative construction of the air outlet device; and

Fig. 6 is a view similar to Fig. 1 illustrating another alternative construction of the air outlet device.

Referring to the drawings in detail, first to Figs. 1 to 4, A designates, generally, an air outlet device constructed in accordance with the invention and B designates, generally, a damper operatively associated with said air outlet device.

According to the specific construction illustrated in the drawings the air outlet device A comprises an outermost, open-ended, hollow, flaring member 10 and a second smaller flaring member 11 which is disposed within and spaced from said outermost member 10 to provide between said members a passageway a which may or may not be of flaring form in cross section but which flares forwardly relative to the longitudinal axis of the device. The device A may comprise only two flaring members, such as the members 10 and 11, or it may comprise any desired plurality of successively smaller, open-ended, hollow, flaring members spaced apart successively inwardly of one another to provide any desired number of flaring passageways for flow of air therethrough. In this connection and as illustrated in Fig. 1 of the drawings, the device A is illustrated as arbitrarily comprising four flaring members; viz., the outermost member 10, the second or next smaller member 11, a third member 12 disposed within and spaced from the member 11 to provide between said members 11 and 12 a passageway b which flares relative to the longitudinal axis of the device, and a fourth member 13 disposed within and spaced from the member 12 to provide between said members 12 and 13 a third flaring passageway c.

The front end portion of the outermost flaring member 10 is directed inwardly, as indicated at 14, relative to the rear portion of said member, while at its smaller or rear end said member 10 is provided with a neck 15 for connection with an air supply duct 16.

The front end portion of the second flaring member 11 preferably is directed outwardly, as indicated at 17, relative to the rear portion of said member so as to intercept air flowing through the passageway a and to cause it to sweep outwardly either across said passageway, or across the front end thereof, depending upon the position of said portion 17 longitudinally of the device relative to the front end of the outermost flaring member 10.

The angularity of the front end portion 14 of the outermost flaring member 10 relative to the rear portion of said member is arbitrarily, but is such, generally speaking, that if air flowing through the passageway a is deflected outwardly against the same, it will, in turn, serve to deflect the air more or less inwardly so as to cause it to leave the passageway a in a direction more or less directly forwardly from the device.

From the foregoing it follows that if the second flaring member 11 is positioned, as indicated by dotted lines in Fig. 1, so that its front end portion 17 causes air flowing through the passageway a to sweep across said passageway against the portion 14 of the outermost flaring member 10, as indicated by the arrow d in Fig. 1, the said portion 14 of the member 10 will intercept and deflect the air so as to cause it to flow more or less directly forwardly from the device as indicated by the arrow e in Fig. 1. It further follows that if, on the other hand, said

second flaring member is positioned as shown by full lines in Fig. 1, so that its front end portion 17 causes the air to be deflected laterally outward across the front end portion 14 of the outermost member 10 as indicated by the arrow f in Fig. 1, said portion 14 will have little or no effect upon the direction of flow of the air and the same therefore will flow from the passageway a more or less only laterally outward from the device. It additionally follows that for positions of the second member 11 intermediate its aforementioned positions, the air will be caused to flow from the passageway a in directions intermediate the directions mentioned.

If the device A comprises only two flaring members, such as the members 10 and 11, the member 11 may be closed at either or both of its ends and all of the air delivered to the device through its neck 15 from the duct 16 therefore will flow through the passageway a. If, on the other hand, the second flaring member 11 is open at its ends and the device includes an additional flaring member, or members, such as the member 12 or the members 12 and 13, which serve to provide one or more additional flaring passageways such as the passageway b or the passageways b and c, some of the air will, of course, flow through the latter passageway or passageways.

In accordance with the invention, the second flaring member 11 and any additional smaller flaring members, such as the members 12 and 13, are, together with adjusting means for the member 11, assembled as a unit, and means are provided whereby this unit may readily and easily be mounted in and removed from the outermost flaring member 10, thus to facilitate installation of the device as well as to afford ready access to its parts for cleaning, repair or other purposes.

The unit mentioned is designated generally as C and includes a shaft 18 which is disposed coaxially with respect to the flaring member 11 and which has its rear or inner end portion suitably provided with a pair of annular members 19, 19 spaced apart longitudinally therealong. These members 19, 19 may be either integral with the shaft 18, or separate therefrom and fixed thereto in any suitable manner; or, as shown, they may be in the form of collars engaged on said shaft between a pair of snap rings 20, 20 or other suitable abutments carried by said shaft. Preferably, however, they are in the form of collars confined between a pair of abutments on the shaft, and preferably, too, suitable spring means, such as a spring washer 21, is interposed between one of the same and one of the abutments 20, whereby they are urged toward one another. In any event, the outer end portions of said members are flanged as indicated at 22.

The unit C further includes a plurality of spider arms 23 which are formed from sheet metal or other suitable sheet material and which are of narrow, inverted U-shape in cross section. Appropriately there may be three of these spider arms. In any event, they are duplicates of one another and extend radially from the rear end portion of the shaft 18, being preferably equi-distantly spaced apart angularly about said shaft.

The inner end portions of the side walls of each of the spider arms 23 are formed as curved arms 24 which embrace the annular members 19, 19 between the flanges 22 of said members. Thus, said spider arms are assembled at their inner ends with the shaft 18 and are maintained tight with respect to said shaft due to

the spring washer 21 serving to urge the annular members 19, 19 toward one another and to the resulting clamping of said arms between the flanges 22.

Between the side walls of each of the spider arms 23 is disposed a lever 25 which is pivoted intermediate its ends to the spider arm as indicated at 26. At its outer end, each lever 25 is suitably pivoted to a related arm 27 which is fixed to and rises from the flaring member 11, while at its inner end each lever 25 is suitably pivoted to a nut 28 which is threaded on the shaft 18 between the annular members 19, 19.

To pivotally connect the levers 25 with the arms 27, the outer end portions of said levers may be rounded and may be disposed in slots formed in said arms and opening through the inner edges thereof. Similarly, to pivotally connect said levers 25 with the nut 28, the latter may have rounded lugs 29 extending therefrom and engaged in slots formed in and opening through the inner ends of said levers. The lugs 29 and the rear or free ends of the arms 27 extend between the side walls of their related spider arms 23. Thus, the side walls of said spider arms hold the nut 28 and the flaring member 11 against rotation and maintain the pivotal connections between the levers 25, the arms 27 and said nut 28. Thus, too, pivot pins are avoided and the pivotal connections between the levers 25, the arms 27 and the nut 28 may readily and easily be effected.

At its front end the shaft 18 is provided with a suitable knob 30 for effecting its rotation. Since the nut 28 is held against rotation, it is apparent that by rotating the shaft 18 the nut 28 may be caused to travel therealong to swing the levers 25 and thus effect longitudinal or forward and rearward adjustments of the flaring member 11.

If the device A should include a third flaring member 12, the spider arms 23 may have depending therefrom arms 31 to which said third flaring member may be secured, while if said device should include a fourth flaring member 13, the latter may be confined at its rear end between the adjacent ends of a pair of sleeves 32 engaged on the shaft 18 between the front abutment 20 and the knob 30, whereby it may be fixed with respect to the third flaring member 12.

The spider arms 23 are of lengths to be accommodated in the neck 15 of the outermost flaring member 10 and at their outer ends are suitably provided with tongues 33 to be entered into and withdrawn from suitable keeper pockets 34 carried by the outermost flaring member 10 by a small amount of rotation of the unit C about its longitudinal axis relative to the outermost flaring member 10.

The pockets 34 are located adjacent to the rear end of the flaring member 10 and, of course, correspond in number and angular spacing to the number and angular spacing of the spider arms 23. Each may be formed by providing a slit in the member 10 and by pressing forwardly a portion of said member adjacent to the slit, or they may be formed by suitably fastening small pieces of U-shape in cross section against the front face of the member 10. In any event, said pockets each have at least one open end so that the tongues 33 may be entered into and withdrawn from the same by a small amount of rotation of the unit C.

In the flaring member 10, adjacent to the end of at least one of the pockets 34 through which

the related tongue 33 is insertable into and removable from said pocket, is an opening 35 through which extends the forwardly directed free end portion 36 of a leaf spring 37 which is concealed behind said flaring member 10. At its other end said leaf spring is suitably fastened to said member 10, while between its ends said leaf spring is provided with a push button 38 which extends forwardly through another opening in the flaring member 10. The free end portion 36 of said leaf spring is disposed to engage the edge of the tongue 33 remote from the pocket 34 when said tongue is disposed in said pocket, thus to prevent rotation of the assembly C relative to the member 10 and to insure against accidental displacement of said unit C from its operative position within the flaring member 10. However, simply by pushing upon the push button 38, the leaf spring 37 may be flexed rearwardly to retract its forwardly directed free end portion 36 from its tongue latching position. The unit C then may be rotated to disengage the tongues 33 from the pockets 34, whereupon said unit is free to be removed from the member 10.

When the unit C is operatively mounted in the outermost flaring member 10, the second flaring member 11 is supported for rearward adjustment to positions in which it is effective to cause air flowing through the passageway a to be deflected outwardly against the portion 14 of the member 10, and for forward adjustment to positions in which it is effective to cause air flowing from said passageway a to be deflected laterally outward across the front end of said member 10. Such adjustments of the member 11 obviously may be effected with facility simply by grasping and rotating the knob 30 which, it will be noted, is disposed at the front of the device, centrally thereof, where it is conveniently accessible.

The button 38 also is located where it is readily accessible from the front of the device through the passageway a whereby mounting of the unit C within, and its detachment from, the outermost flaring member 10 may be accomplished with facility.

By way of example it may be pointed out that when heated air is delivered through the device A for room or enclosure heating purposes, it may be desirable to have the air flow more or less directly forwardly from the device, while when cool air is supplied through the device for room or enclosure cooling or ventilating purposes, it may be desirable to have the air flow primarily laterally outward from the device. Regardless of whether any particular device includes only a single air passageway, such as the passageway a, or additional smaller passageways, such as the passageways b and c, the direction in which air leaves the passageway a primarily determines the general direction in which air flows from the device. Manifestly, therefore, the provision for longitudinal adjustments of the second flaring member 11 enables the direction of flow of air from the device to be regulated as desired.

In many instances it may be desirable to use, in association with an air outlet device such as the device A, a damper to regulate flow of air from the duct 16 to the device A. In any such instance, the shaft 18 of the device A may conveniently be employed as a supporting and guiding means for means for adjusting the damper B.

The damper B is illustrated by way of example as of the swinging vane type and as comprising a rectangular housing 40 which is open at its front

and rear ends for flow of air therethrough and which may be mounted in any suitable manner in the duct 16 directly behind the air outlet device A so that air flowing from said duct through said housing enters the neck 15 of the device A.

The damper B further comprises a rectangular frame 41 which, like the housing 40, is open at its front and rear ends for flow of air therethrough and which is hinged at one end to one end of the housing 40, as indicated at 42, for swinging movements between a position within and parallel to said housing 40, as illustrated by full lines in Fig. 1, and different positions of rearward inclination relative to said housing, one of which is indicated by dotted lines.

Extending across the frame 41 at points spaced longitudinally therealong is a plurality of vanes 43 which are of L-shape in cross section and which are pivoted at their ends, intermediate their side edges, to the sides of the frame 41, as indicated at 44, whereby they are individually rotatable with respect to said frame.

Each vane 43 includes a rear portion 45 which is disposed substantially parallel to the housing 40, and a front or forwardly extending portion 46 which is disposed at substantially right angles to the rear portion 45. The front portions 46 of said vanes are pivotally connected, as indicated at 47, to a bar 48, and said bar is pivoted at one end, as indicated at 49, to the housing 40 at a point adjacent to and forwardly of the hinge 43. The frame 41, the vanes 43 and the bar 48 thus constitute a parallelogram structure which is swingable between the full line position shown in Fig. 1 and rearwardly inclined positions relative to the housing 40, as indicated by dotted lines in Fig. 1.

When the frame 41 is disposed within and parallel to the housing 40, as shown by full lines in Fig. 1, the rear end portions 45 of the vanes 43 are disposed in a common plane parallel to the frame 41 and said housing 40 and in edge to edge relationship so that they substantially completely close said frame 41 and prevent any flow of air therethrough from the duct 16 to the device A. When, however, the frame 41 is swung rearwardly to any position of inclination relative to the housing 40, the rear portions 45 of the vanes 43 become spaced apart due to the bar 48 constraining said vanes to rotate about their pivots as they swing bodily rearwardly with said frame 41. In other words, the parallelogram structure including the vanes 43 maintains the rear portions 45 of said vanes in planes parallel to each other. Consequently, as the frame 41 is swung rearwardly, the rear portions 45 of the vanes 43 progressively separate and assume a stepped or echeloned relationship to each other so that air may flow between them. In this connection, the damper B is, of course, mounted in the duct 16 so that the free edges of the portions 45 of the vanes 43 face counter to the direction of flow of air through said duct. It follows, therefore, that as the frame 41 is swung rearwardly, air enters between the rear portions 45 of the vanes 43 and is deflected forwardly into the outlet device A by the front portions 46 of said vanes. In addition to being effective to accurately regulate the amount of air delivered to a device such as the device A, a special advantage of a damper of the type illustrated and described is that it is effective to distribute the air substantially uniformly to all parts of the device A.

For swinging the swingable parts of the damper B, there is provided a rod 49 which is suitably

connected at its rear end to some swinging part of said damper, such as the bar 48, and which extends forwardly therefrom. In this connection and in accordance with the present invention, the shaft 18 is hollow and contains another hollow shaft or tube 50 into which the rod 49 extends. The shaft, or tube 50 is rotatable relative to the shaft 18, but is suitably held against longitudinal movement relative thereto. The rod 49 is threaded and has threaded connection either directly with the shaft or tube 50 or, as shown, with a nut 51 suitably fixed to said shaft or tube 50. In any event, since said shaft or tube 50 is held against longitudinal movement by the shaft 18 and has threaded connection with the rod 49, it follows that rotation of said shaft or tube 50 will result in longitudinal movement of said rod 49 which, in turn, will result in swinging of the frame 41. Obviously, depending upon the direction and the amount of rotation of the shaft or tube 50, the frame 41 may be swung to a closed position as shown by full lines in Fig. 1 to deny flow of air from the duct 16 to the outlet device A, or to any of an infinite number of angular positions relative to the housing 40 to admit more or less air from said duct to said outlet device.

While any suitable means may be employed to hold the shaft or tube 50 against longitudinal movement relative to the shaft 18, suitable means for this purpose may comprise a flange 52 at the rear end of the shaft or tube 50 overlying the rear end of the shaft 18 to hold said shaft or tube 50 against forward movement relative to said shaft 18, and a spring finger 53 at the front end of said shaft or tube 50 engaging a forwardly facing shoulder 54 at the front end of said shaft 18 to hold said shaft or tube 50 against rearward movement relative to said shaft 18. The flange 52 may comprise part of the nut 51 and the spring finger 53 may frictionally engage the inner face of the shaft 18 to hold the shaft or tube 50 in any position of rotation to which it may be adjusted.

While any suitable means may be provided to facilitate rotation of the shaft or tube 50, said shaft may appropriately be provided at its front end with a slot 55 with which a screw driver or other suitable turning tool may be engaged. The slot 55 may be provided in a plug 56 for closing the front end of said shaft or tube 50 and said plug may be employed as a fastening means for the spring finger 53. In other words, the spring finger 53 may include an anchoring portion 57 confined between the plug 56 and the inner face of the shaft or tube 50.

As will be apparent from the foregoing, the shaft 18 of the present outlet device A constitutes a supporting and guiding means for the means for adjusting a damper either of the swinging vane type, as shown, or of a type adjustment of which is effected by swinging or other forward and rearward movement of an air flow regulating member or members.

Referring now to the alternative construction illustrated in Fig. 5 of the drawings, 23' designates spider arms corresponding to the spider arms 23 of the Figs. 1 to 4 construction, and 19', 19' designate a pair of annular members corresponding to the annular members 19, 19 of the Figs. 1 to 4 construction and between which the inner ends of the spider arms 23' are confined as in the Figs. 1 to 4 construction. A shaft 18', corresponding to the shaft 18 of the Figs. 1 to 4 construction, extends through the members 19', 19' and carries at its rear end a nut or other suit-

able abutment 58 and at its front end a nut or other suitable abutment 59. Between the abutment 58 and the rearmost of the members 19' is interposed suitable yieldable means such as a helical expansion spring 60 which may surround the shaft 18', while between the abutment 59 and the rear end of the smaller or innermost flaring member 13', which is maintained spaced from the forwardmost member 19' by a sleeve 32' as in the Figs. 1 to 4 construction, is interposed a bellows 61. Thus, the spring 60 tends constantly to shift the shaft 18' rearwardly and to compress the bellows 61, and said bellows is effective, by expansion, to shift said shaft 18' forwardly.

Between the members 19', 19' the shaft 18' is provided with external screw threads 62 which may be formed either directly upon said shaft or, as shown, upon a sleeve 63 welded or otherwise suitably fixed to said shaft. In any event, a nut 28', corresponding to the nut 28 of the Figs. 1 to 4 construction, is engaged with said screw threads 62 and is connected with arms 25', corresponding to the arms 25 of the Figs. 1 to 4 construction, in the same manner as the nut 28 is connected to the arms 25.

As will be apparent from the foregoing, the shaft 18' is effective, either by longitudinal movement thereof relative to its supporting spider arms 23', or by rotation, to shift the nut 28' forwardly or rearwardly and thus swing the levers 25' to adjust the second flaring member of the device either forwardly or rearwardly relative to the outermost flaring member of the device.

Forward movement of the shaft 18' may be effected by admitting a suitable fluid under suitable pressure to the bellows 61 to expand the same, and admission and escape of such fluid to and from said bellows may be under either manual control or, if desired, under thermostatic control, whereby the second flaring member is adjusted in accordance with changes in temperature of the air delivered through the outlet device. If the admission of fluid to and from the bellows 61 is under thermostatic control, rotation of the shaft 18' need only be employed to effect a desired initial adjustment of the second flaring member of the device, since thereafter automatic longitudinal movement of said shaft 18', in one direction by the spring 60 and in the other direction by the bellows 61, will be effective to produce required adjustments of said second flaring member.

Fig. 6 of the drawings illustrates a construction which is generally the same as the Figs. 1 to 4 construction, except that arms 64, rigidly connected to the second flaring member of the device, are employed in lieu of the pivoted levers 25 of the Figs. 1 to 4 construction.

While the members 10, 11, 12 and 13 have been illustrated by way of example as being of flaring form, it is desired to point out that some or all of said members may be of more or less flat or disk-like or of any other desired form within the purview of the invention.

From the foregoing description considered in connection with the accompanying drawings, it is believed that the construction and operation of the invention will be clearly understood and its advantages appreciated. It is desired to point out further, however, that while only certain specific structures have been illustrated and described, the invention is readily capable of embodiment in specifically different structures

within its spirit and scope as defined in the appended claims.

We claim:

1. A device for delivery of air into an enclosure, said device comprising a first member of hollow flaring form open at its ends for flow of air therethrough from its smaller end toward its larger end, a second member of flaring form smaller than said first member and spaced inwardly from the latter to effect lateral deflection of air flowing through said first member, and means securing said second member to said first member for longitudinal adjustments relative to the latter to vary the direction of lateral deflection of air from the device, said securing means including a threaded shaft disposed coaxially with said members, means holding said shaft against longitudinal movement, a nut threaded on said shaft, means holding said nut against rotation whereby it is movable along said shaft by rotation of the latter, and levers pivotally supported intermediate their ends by said first member and operatively connected at their ends to said nut and said second member, respectively, whereby longitudinal movements of the former effect longitudinal adjustments of the latter.

2. A device for delivery of air into an enclosure, said device comprising a first member of hollow flaring form open at its ends for flow of air therethrough from its smaller end toward its larger end, a second member of flaring form smaller than said first member and spaced inwardly from the latter to effect lateral deflection of air flowing through said first member, spider arms connected to said first member, a threaded shaft supported coaxially with said members by said spider arms for rotation and for longitudinal movements, means for longitudinally moving said shaft and for resisting its longitudinal movement from any position to which it may be longitudinally adjusted, a nut threaded on said shaft for longitudinal adjustments therewith and held against rotation whereby it is adjustable along said shaft by rotation of the latter when longitudinal movement of the same is resisted, and connections between said nut and said second member whereby the latter is supported in said first member for longitudinal adjustments relative thereto and is longitudinally adjustable by longitudinal adjustments of said nut with said shaft.

3. A device for delivery of air into an enclosure, said device comprising a first member of hollow flaring form open at its ends for flow of air therethrough from its smaller end toward its larger end, a second member of flaring form smaller than said first member and spaced inwardly from the latter to effect lateral deflection of air flowing through said first member, spider arms connected to said first member, a threaded shaft supported coaxially with said members by said spider arms for rotation and for longitudinal movements, spring means for moving said shaft longitudinally in one direction and fluid pressure means for moving said shaft longitudinally in the opposite direction whereby it is longitudinally adjustable and is held against longitudinal movement from any position to which it may be longitudinally adjusted, a nut threaded on said shaft for longitudinal adjustments therewith and held against rotation whereby it is longitudinally adjustable along said shaft by rotation of the latter when the same is held against longitudinal movement, and connections between said nut and said second member whereby the

latter is supported in said first member for longitudinal adjustments relative thereto and is longitudinally adjustable by longitudinal adjustments of said nut with said shaft.

4. A device for delivery of air into an enclosure, said device comprising a first member of hollow flaring form open at its ends for flow of air therethrough from its smaller end toward its larger end, a second member of flaring form smaller than said first member and spaced inwardly from the latter to effect lateral deflection of air flowing through said first member, and means mounting said second member for adjustments longitudinally relative to said first member to vary the direction of discharge from the device of air delivered through the device between said members, said mounting means comprising an adjusting element disposed axially of the device and mounted for adjustment longitudinally of the device, means exposed at the front of the device centrally thereof for adjusting said element longitudinally of the device, a spider arm fixed to and extending inwardly from said first member and serving as a support for said mounting means, an arm connected at one end to said second member and having a laterally separable connection at its other end with said adjusting element, said spider arm having spaced apart said walls disposed to either side of said laterally separable connection and holding the latter normally against separation.

5. A device for delivery of air into an enclosure, said device comprising a first member of hollow flaring form open at its ends for flow of air therethrough from its smaller end toward its larger end, a second member of flaring form smaller than said first member and spaced inwardly from the latter to effect lateral deflection of air flowing through said first member, a shaft supported by said first member coaxially with said members, means whereby said second member is adjustable by said shaft longitudinally relative to said first member to vary the direction of discharge of air from the device, a damper disposed behind said device and including means movable forwardly and rearwardly relative to said device to regulate the supply of air to said device, a threaded actuating rod for the said movable means of said damper extending forwardly from said movable means, said shaft being hollow, and a second hollow shaft mounted in said first shaft for rotation and held against longitudinal movement relative thereto, said rod extending into said second shaft and having threaded connection therewith whereby it is longitudinally adjustable to actuate the movable means of said damper by rotation of said second shaft.

6. A device for delivery of air into an enclosure, said device comprising a first member of hollow flaring form open at its ends for flow of air therethrough from its smaller end toward its

larger end, a second member of flaring form smaller than said first member and spaced inwardly from the latter to effect lateral deflection of air flowing through said first member, a hollow shaft supported by said first member coaxially with said members, means whereby said second member is adjustable by said shaft longitudinally relative to said first member to vary the direction of discharge of air from the device, a damper disposed behind said device for regulating the supply of air to the latter, an adjusting rod for said damper extending into said shaft, and means accessible at the front end of said shaft for adjusting said rod longitudinally relative to said shaft to regulate said damper.

7. A device for delivery of air into an enclosure, said device comprising a first member of hollow flaring form open at its ends for flow of air therethrough from its smaller end toward its larger end, a second member of flaring form smaller than said first member and spaced inwardly from the latter to effect lateral deflection of air flowing through said first member, a hollow shaft supported by said first member coaxially with said members, means whereby said second member is adjustable by said shaft longitudinally relative to said first member to vary the direction of discharge of air from the device, a damper disposed behind said device for regulating the supply of air to the latter, a threaded adjusting rod for said damper extending into said shaft, and an element in said shaft with which said rod has threaded connection and which is rotatable to longitudinally adjust said rod to regulate said damper.
